HANDLE FOR A UTILITY KNIFE

Thomas Lamb, Mariomi Road, New Canaan, Conn.

Filed Oct. 1, 1959, Ser. No. 57,747

Term of patent 14 years

(Cl. D22—3)

Fig. 1.

Fig. 2.

Fig. 3.

Figure 1 is a side elevational view of a utility knife embodying my new design, the side opposite thereto being identical in appearance.

The conventional portions of a utility knife shown in dotted lines in Figures 1, 2 and 3 are only for the purpose of illustration.

I claim:

The ornamental design for a handle for a utility knife, substantially as shown and described.
